UNITED STATES PATENT OFFICE.

HARVEY C. SHAMBLIN, OF COMMERCE, OKLAHOMA.

WRENCH.

1,202,905.

Specification of Letters Patent.

Patented Oct. 31, 1916.

Application filed April 6, 1916. Serial No. 89,315.

To all whom it may concern:

Be it known that I, HARVEY C. SHAMBLIN, a citizen of the United States, residing at Commerce, in the county of Ottawa and 5 State of Oklahoma, have invented certain new and useful Improvements in Wrenches; and I do hereby declare the following to be a full, clear, and exact description of the invention, such as will enable others skilled 10 in the art to which it appertains to make and use the same.

This invention relates to wrenches and particularly to wrenches for pipes; and it 15 consists in the novel construction and combination of the parts hereinafter fully described and claimed.

In the drawings, Figure 1 is a side view 20 of a wrench constructed according to this invention. Fig. 2 is a longitudinal section through the wrench, taken on the line $x-x$ in Fig. 1. Fig. 3 is a section taken on the line $y-y$ in Fig. 2, and drawn to a larger scale.

The wrench is provided with a handle 25 having a longitudinal socket 3 at its upper end portion. A non-slidable wrench jaw 30 is provided, and has a shank 4 which is pivoted by a pin 5 in one side of the upper end portion of the socket 3. A slidable 30 wrench jaw 6 is provided and has a long shank 7 which is slidable longitudinally in the other side portion of the socket.

A longitudinal groove 8 is formed in one 35 side of the slidable shank 7, and 9 is a screw which engages with the side wall of the socket and projects into the groove 8. The lower end 10 of the groove forms a stop which prevents the shank from sliding out of the socket altogether, by coming in contact with the end portion of the screw. The 40 other side of the shank 7 is provided with a rack 12 having ratchet-shaped teeth which are sunk below its surface. The socket 3 has a chamber 14 formed on one side of its 45 upper end portion over the rack 12. A short shaft or pin 15 is journaled in bearings in the sides of the chamber 14, and a head or knob 16 is provided on one end of the shaft 15. The other end portion of the 50 shaft has a screwthreaded portion 17 and a nut 18, and the head 16 has a notch 19 to

enable the shaft to be held from revolving while the nut 18 is being screwed up tightly. A pawl 20 is secured on the shaft 15 inside the chamber, and a helical spring 21 is arranged between the pawl and one end of the chamber, so as to normally hold the pawl in engagement with the toothed rack and prevent the slidable shank from moving outwardly. 55

The shaft 15 has a lateral projection 22 on one side, and a slot is formed in the pawl. The projection fits in the slot of the pawl like a key so that the pawl never slips circumferentially on the shaft. The hole in 60 the side of the chamber next to the knob is elongated to permit the part 22 to pass through it, and the spring holds the shaft against one side of this hole. 65

The wrench jaws are moved toward each 70 other by simply pushing in the slidable jaw and its shank. When the jaws are to be separated the knob 16 is turned by hand so as to release the slidable shank from the pawl. 75

This wrench is simple to construct and is very rapid in adjustment. The knob 16 is arranged in the angle formed between one side of the chamber and the socket, where it is protected from injury so that it cannot 80 get broken off. The chamber 14 is formed integral with the socket and handle; and the projection 22 is formed integral with the pawl shaft, so that there are no loose parts which are liable to be broken off or 85 displaced.

What I claim is:

1. In a wrench, a handle provided with a socket having a laterally projecting chamber on one side of it, a non-slidable jaw, a slidable 90 jaw provided with a shank which is slidable in the said socket and which has a toothed rack on one side, a shaft journaled in the sides of the said chamber and provided with an operating knob arranged in 95 the angle between the chamber and socket, and a spring-pressed pawl secured on the said shaft inside the chamber and normally engaging with the toothed rack.

2. In a wrench, a handle provided with a 100 socket having a laterally projecting chamber on one side of it, a non-slidable jaw, a slid-

able jaw provided with a shank which is
slidable in the said socket and which has
a toothed rack on one side, a shaft journaled
in the sides of the said chamber and pro-
vided with a lateral projection at its middle
part inside the chamber and having an
operating knob on one end, and a spring-

pressed pawl mounted on the said shaft and
its projection and normally engaging with
the toothed rack.

10

In testimony whereof I have affixed my
signature.

HARVEY C. SHAMBLIN.
